US0D1112122S

(12) **United States Design Patent** (10) **Patent No.:** **US D1,112,122 S**
(45) **Date of Patent:** **** Feb. 10, 2026**

(54) **COVER FOR ELECTRONIC DEVICE**

(71) Applicant: **OYSTASHELL IP LIMITED**,
Northampton (GB)

(72) Inventor: **Martin Patrick Kearney**, Northampton
(GB)

(73) Assignee: **OYSTASHELL IP LIMITED**,
Northampton (GB)

(**) Term: **15 Years**

(21) Appl. No.: **29/872,208**

(22) Filed: **Mar. 8, 2023**

(30) **Foreign Application Priority Data**

Sep. 20, 2022 (GB) 6232781

(51) **LOC (15) Cl.** **13-03**
